FIRE ALARM APPARATUS

Michael P. Reece, London, England, assignor, by
mesne assignments, to Pyroban Developments
Limited, Manchester, England, a body corpo-
rate of Great Britain

Application November 18, 1948, Serial No. 60,790
In Great Britain November 25, 1947

2 Claims. (Cl. 177—355)

1

This invention relates to improvements in fire alarm apparatus of the type in which a rise in temperature of the surrounding air causes the apparatus to operate.

According to the invention a pair of resistor elements are connected in series with the coil of a polarized relay, a predetermined rate of temperature rise in the ambient temperature of the air upsetting the balance of the polarized relay to operate an alarm signal.

A further feature of the invention is the provision of a further coil in the main circuit capable of operating indicating mechanism for fault location.

The invention will be described with reference to the accompanying drawings:

Fig. 1 is a circuit diagram showing one embodiment of the invention;

Fig. 2 is a circuit diagram showing a modified embodiment;

Fig. 2a shows a modified detail modification of Fig. 2;

Fig. 3 is a side elevation, partly in section, at an enlarged scale of a detector head shown in Figs. 1 and 2;

Fig. 4 is a side elevation partly in section of same at right angles to Fig. 3; and

Fig. 5 is a plan of same.

The apparatus comprises one or more detector heads 1 connected in series where more than one is employed. Each detector head 1 comprises two resistor elements *a*, *d* (see also Figs. 3 and 4) one element *a* being wound on a skeleton former 2 more fully to be described presently with adjacent turns separated so as to present a large surface area in relation to its weight. The second element *d* is wound on the same former, with its varnished turns close together and overlapping so as to provide a small surface area in relation to its weight. The former 2 comprises a base plate 3 having four fabric covered rods 4 around which the elements *a* and *d* are wound. The turns of the second element *d* may be lagged with glass wool or other heat insulating material so as to further retard the effect of the surrounding air thereon.

The ends of the windings of the elements *a* and *d* are brought out to four terminals 5 on the base plate 3. A resistance strip *c* may be connected in series with the winding *a*, this strip *c* being normally short circuited by a spring *b* preferably of Phosphor bronze anchored at one end by a bead 6 of low melting point alloy. The other end of the spring *b* is carried by a pillar

2

7 mounted on the base plate 3. The former 2 is suspended from a ceiling or in any other suitable position so that air may circulate freely around the elements. The base plate and terminals are enclosed in a cover 8 carried by a spindle 9 secured to the former 2, the cover leaving a clearance space between the ceiling or other surface and the base of the cover so as to allow the circulation of air over the winding of the element *a*.

The two elements *a* and *d* are connected in parallel across a D. C. supply 91 through a polarized relay 51 and a potentiometer R¹. One end of each element *a* and *d* is connected in series with 15 a coil *e* or coil *f*, respectively, of the polarized relay 51, the two coils *e* and *f* of which are wound in opposition, the free ends of the coils *e* and *f* being connected by the potentiometer R¹, the movable contact R'' of which is fed from one 20 terminal of the D. C. supply 91 through the main circuit. The D. C. supply may be obtained from a battery or through a rectifier from A. C. mains.

The polarized relay 51 is adjusted by moving the contact R'' and the potentiometer R¹ so that 25 at normal temperatures the currents passing through the coils *e* and *f* are equal and balance each other, and no resultant magnetism is available which could operate in the manner more fully described hereinafter a relay circuit 71 containing an alarm device such as a red lamp 61 and/or an audible alarm bell or gong 81. However, if the temperature rises, the resistance in 30 the main circuit will vary and the relay circuit will be operated.

The warning circuit is operated by a reed 11 suspended between the coils *e* and *f*, the free end of the reed normally resting between two contacts *h* and *g*, the contact *g* being connected to the lead 61' to the lamp 61. The reed 11 makes 35 contact with the contact *g* if any current being out of balance should circulate in the coil *f*. The relay circuit 71 comprises a coil 12 and two pairs of contacts 13 and 14. When the reed 11 makes contact with the contact *g* the coil 12 is energised so as to close the contacts 13 and 14, the closing of the contacts 13 operating the alarm device 81.

The second pair of contacts 14 are connected in 40 a resetting circuit in series with a variable resistance R² across the coil *f* and part of the potentiometer R¹. The closing of the contacts 14 reduces the current flowing in the compensating winding *f* of the polarized relay 51 and causes the reed 11 to leave the contact *g* thereby resetting the circuit.

If the disturbing conditions i. e. the increase

in temperature of the air impinging on the detector head still exists, the reed 11 will again make contact with contact 9 and the cycle of operations will be repeated until the disturbing conditions are removed. The circuit will thereafter remain reset.

The lamp 61 will flash intermittently but the arrangement of the contact 14 may be such that the bell 81 will ring continuously.

The operation of the device shown in Fig. 1 is as follows: On the closing of a switch 10 current flows in each of the parallel windings *a* and *d* through the detector head 1 and through coils *e* and *f* of the polarized relay, the ratio of the two currents being adjustable by means of the potentiometer R^1 . When any out of balance current flows in either coil *e* or *f* due to change in the resistance of either winding *a* or *d* due to change in temperature the reed 11 is operated to make contact with the contact 9 to operate the alarm device.

An out of balance current can be caused also with a slow rise of temperature which acts substantially at the same rate on both windings *a* and *d* by firing the strip of low melting anchoring bead 6 of the spring *b* so that the short-circuit of the strip *c* is removed and the windings *a* and *d* carry different currents thereby unbalancing the circuit and causing the operation of the alarm devices.

The arrangement shown in Fig. 2 is applicable for industrial purposes such as for use in coal mines, on aircraft, or other applications. The main circuit is similar to that hereinbefore described, but includes a "fault" relay 15. The potentiometer R^1 may be replaced by a potentiometer R^3 in series with the coil *f* (Fig. 2a) and has a tapping point in series with the relay 15 which provides a somewhat finer adjustment.

The coil of the relay 15 is of low resistance and the current normally flowing in the main circuit is arranged so as to hold contacts 16 closed. Should the current fall below a predetermined value the relay contacts 16 open and contacts 17 close. The closing of contacts 17 illuminates a lamp 18 which may be coloured amber and indicating a circuit fault. Simultaneously a relay coil 19 is energised to close contacts 20 and sound a fault indicating buzzer 21. Thus if any of the leads to the head 1 are severed or the heads 1 themselves are damaged the current flowing in the main circuit will fall in value and the fault finding circuit will give an indication thereof. A similar operation of the relay 19 occurs if the supply of current to the main circuit drops. For use in mines plate rectifiers may be arranged in parallel with the coils so as to reduce sparking.

The opening of the contacts 16 of the relay 15 also opens the circuit of the reed 11 of the polarized relay 51 thereby preventing a spurious operation of the fire alarm device.

Where a number of units each comprising one or more heads are employed the position of the relay 19 and the lamp 18 may be reversed so that each unit is provided with a lamp 18 operated in parallel from a single relay 15 which will cause the lamp in the faulty circuit to be illuminated and also operate the buzzer 21.

In order to indicate normally that the circuit is operating the reed 11 rests in contact with the contact *h* in series with a lamp 22 which may be coloured green.

A push button switch 221 may be provided in order to prevent the circuit from being reset automatically so that the circuit remains in its

alarm condition until reset manually by operation of the switch 221.

A test circuit may be incorporated by introducing a single pole two way switch 23 which normally completes the circuit between the rheostat R^2 and point 24 but which when operated connects the potentiometer R^2 to a point 25 thereby putting the potentiometer R^2 in shunt with the winding *e* thus reducing the current flowing therein and simulating a disturbing condition at the heads 1.

In cases where relatively high temperatures are normal such as in aircraft engines the detector heads may be constructed on ceramic formers and the elements *a* and *d* may consist of tungsten wire so as to only operate when a predetermined temperature has been exceeded.

Four heads 1 are shown in series in the drawings but one or two or up to twelve or more may be employed.

I claim:

1. A fire alarm apparatus comprising in combination a current source; a detector head; a first resistor element and a second resistor element arranged in said head and each connected with one end thereof to a terminal of said current source; a polarized relay having a first coil and a second coil wound in opposition to said first coil, said first coil being connected in series with said first resistor element and said second coil being connected in series with said second resistor element; a potentiometer connecting said first coil and said second coil with each other so as to provide a balanced circuit at normal temperatures; a reed arranged between said coils of said polarized relay for deflection out of its normal position by any out-of-balance currents flowing in said polarized relay; a contact arranged at the free end of said reed; a secondary circuit energized by the closing of said contact of said reed so as to be closed when an out-of-balance current flows in said polarized relay; a first relay in said secondary circuit, said first relay being energized when an out-of-balance current flows in said polarized relay; a pair of contacts operated by said relay so as to be closed upon the energization thereof; a warning device connected in series to said pair of contacts so as to be operated when an out-of-balance current flows in said polarized relay; a second relay connected to said current source; a first pair of contacts operated by said second relay and connected in series to said reed, said first pair of contacts opening when the current through said second relay falls below a predetermined value and thus interrupting said secondary circuit in order to prevent a spurious operation of said warning device; a second pair of contacts operated by said second relay, said second pair of contacts closing when the current through said second relay falls below the predetermined value; and a fault-indicating device connected to said second pair of contacts so as to be operated by the closing thereof simultaneously with the opening of said first pair of contacts of said second relay.

2. A fire alarm apparatus comprising in combination a current source; a detector head; a first resistor element and a second resistor element arranged in said head and each connected with one end thereof to a terminal of said current source; a polarized relay having a first coil and a second coil wound in opposition to said first coil, said first coil being connected in series with said first resistor element and said sec-

ond coil being connected in series with said second resistor element; a potentiometer connecting said first coil and said second coil with each other so as to provide a balanced circuit at normal temperatures; a reed arranged between said coils of said polarized relay for deflection out of its normal position by any out-of-balance currents flowing in said polarized relay; a contact arranged at the free end of said reed so as to be closed when an out-of-balance current flows in said polarized relay; a secondary circuit energized by the closing of said contact of said reed; a first relay in said secondary circuit, said first relay being energized when an out-of-balance current flows in said polarized relay; a pair of contacts operated by said relay so as to be closed upon the energization thereof; a warning device connected in series to said pair of contacts so as to be operated when an out-of-balance current flows in said polarized relay; a second relay connected to said current source; a first pair of contacts operated by said second relay and connected in series to said reed, said first pair of contacts opening when the current through said second relay falls below a predetermined value and thus interrupting said secondary circuit in order to prevent a spurious operation of said warning device; a second pair of contacts operated by said second relay, said second pair of contacts closing when the current through said second relay falls below the prede-

termined value; a fault-indicating device connected to said second pair of contacts so as to be operated by the closing thereof simultaneously with the opening of said first pair of contacts of said second relay; a rheostat; and a single pole two way switch for connecting one of said coils of said polarized relay in shunt with said rheostat in order to reduce the current in said coil thereby simulating a disturbing condition at said detector head.
